[57] ABSTRACT

An eraser attachment for ball point pens including a resilient cylindrical body portion which encompasses the ball point pen and has a notch for engaging under the clip of the ball point pen to prevent the body from turning on the pen. A cylindrical socket is secured to the side of the body opposite the clip notch to support a generally cylindrical eraser therein. The eraser socket has its axis extending perpendicularly to the axis of the body so that the eraser extends outwardly from the pen.

3 Claims, 6 Drawing Figures

FIG. 1.**FIG. 2.****FIG. 3.****FIG. 4.****FIG. 5.****FIG. 6.**## ERASER FOR BALL POINT PEN

BACKGROUND OF THE INVENTION

1. Field of the Invention

The present invention relates to eraser attachments for ball point pens.

2. Summary of the Invention

The eraser attachment for ball point pens of the instant invention includes a generally cylindrical resilient body adapted to encompass a cylindrical ball point pen with the body provided with a notch to engage under the clip of the pen to prevent the body from turning on the ball point pen. A generally cylindrical socket extends perpendicularly to the body to receive an eraser with the eraser projecting outwardly of the body for use.

The primary object of the invention is to provide an eraser attachment for ball point pens.

Other objects and advantages will become apparent in the following specification when considered in light of the attached drawings.

BRIEF DESCRIPTION OF THE DRAWINGS

FIG. 1 is a perspective view of the invention; FIG. 2 is a perspective view of the invention shown partially from the rear;

FIG. 3 is a top plan view of the invention;

FIG. 4 is a vertical sectional view, taken along the line 4-4 of FIG. 3, looking in the direction of the arrows;

FIG. 5 is a rear elevation of the invention; and

FIG. 6 is an exploded perspective view of the invention shown removed from the ball point pen with a modified form of eraser.

DESCRIPTION OF THE PREFERRED EMBODIMENTS

Referring now to the drawings in detail, wherein like reference characters indicate like parts throughout the several figures, the reference numeral 10 indicates generally an eraser attachment for ball point pens constructed in accordance with the invention.

The eraser attachment 10 is adapted for use with a ball point pen 11 of conventional design and including a pocket clip 12 and a hand actuated plunger 15 for exposing the writing point of the pen when desired. The pen 11 is generally cylindrical in form and its construction is completely conventional forming no part of the present invention.

The attachment 10 includes a resilient generally cylindrical body 14 which is split along a line 15 parallel to the axis of the body 14. A generally rectangular notch 16 is formed in the top edge of the body 14 to permit the body 14 to have resiliency for gripping the pen 11. The notch 16 engages around the base of the pocket clip 12 so as to prevent the body 14 from rotat-

ing around the pen 11 as the attachment 10 is used.

A generally cylindrical eraser socket 17 is integrally formed with the body 14 and has its axis extending perpendicularly to the axis of the body 14.

5 A generally resilient eraser 18 is adhesively secured in the socket 17 to complete the attachment 10. In the use and operation of the eraser attachment 10 the body 14 is slid upwardly along the pen 11 under the clip 12 until the rectangular notch 16 engages the base of the 15 clip 12 which acts as a stop to position the attachment 10 for use.

In FIG. 6 a modified eraser attachment for ball point pens is illustrated generally at 10'. The structure of the attachment 10' includes a body 14' identical to the body 14 and including a generally cylindrical socket 17' identical to the socket 17. An eraser 18' is fitted into a resilient base 19 and is in turn seated in the socket 17' to thus provide the replaceable eraser for the eraser attachment 10'.

20 The use and operation of the modified form of the invention illustrated in FIG. 6 is identical to that of the form of the invention illustrated in FIGS. 1 through 5.

Having thus described the preferred embodiments of the invention it should be understood that numerous structural modifications and adaptations may be resorted to without departing from the spirit of the invention.

What is claimed is:

1. In an eraser attachment for ball point pens of the type that include a pocket clip and a hand actuated plunger, a generally cylindrical body adapted to encompass the ball point pen, a generally cylindrical eraser socket integrally secured to said body and projecting outwardly therefrom with its axis perpendicular to the axis of said body, means on said body cooperating with said pocket clip for preventing rotation of said body on said ball point pen during use of said eraser attachment, a generally resilient eraser seated in said socket, the means for preventing rotation of said body including a generally rectangular notch formed in the upper edge of said body for engaging around the base of said pocket clip to prevent the body from rotating around the pen as the eraser attachment is used and from moving longitudinally of the pen in one direction, said body being resilient and having a longitudinal split parallel to the axis of the body to permit said body to resiliently grasp the ball point pen, the upper edge of said split communicating with said notch, said socket being positioned generally in diametrically opposed relation relative to said notch and split.

2. A device as claimed in claim 1 wherein the eraser is adhesively mounted in the socket on said body.

3. A device as claimed in claim 1 wherein the eraser is removably seated in the socket on said body.
